UNITED STATES PATENT OFFICE.

HORATIO N. NORTON, OF MOUNT VERNON, NEW YORK.

CLOSURE FOR CONTAINERS.

937,847.

Specification of Letters Patent.

Patented Oct. 26, 1909.

Application filed January 30, 1908. Serial No. 413,439.

To all whom it may concern:

Be it known that I, HORATIO N. NORTON, a citizen of the United States, and a resident of Mount Vernon, in the county of 5 Westchester and State of New York, have invented certain new and useful Improvements in Closures for Containers, of which the following is a specification.

This invention relates to closures for containers, with particular reference to closures which may not only be easily and readily applied to containers of either glass or metal and provide an air-tight seal, but which may be quickly removed without the employment of any form of tool or implement when 10 it is desired to have access to the contents of the package.

The present invention does not so much contemplate any radical departure from the 20 general principles involved in a form of closure which has for some time been known and used, but has in view, first, the assembling of the members of a two-part closure which have heretofore been made, sold and 25 applied individually, in such manner that the two parts are self-secured together to facilitate handling, packing, delivery and application as single articles of manufacture; and, second, to still further improve 30 upon one of the parts of such closure, as hereinafter described.

My invention will be more readily understood by reference to the accompanying drawings, forming part of this specification, 35 in which—

Figure 1 is a perspective view of the two parts of a closure embodying my invention, when assembled; Figs. 2 and 3 are similar views of the two parts shown separately; 40 Fig. 4 is a central section of the closure as applied to a glass containing vessel, and Fig. 5 is a central sectional elevation of the closure as applied to a sheet metal container, commonly known as a tin can.

45 The glass bottles or jars to which my closure is adapted to be applied (the neck 11 of such vessel being shown in Fig. 4) are each provided with an annular rim at its mouth which forms the shoulder 12. Fitting over 50 the mouth of the bottle is the ordinary slip-cover 13 with the depending flange 14 the lower edge of which terminates short of the shoulder 12 in the neck of the bottle. The major middle portion 15 of said slip cover 55 is preferably depressed to form an annular seat or socket for the reception of a packing

ring 16, which may be of rubber, pulp-board or other suitable material.

Surrounding the covered mouth of the vessel is the binding-strap 17, in the form of 60 an open ring with butting ends, one thereof being provided with an overlapping tongue 18. This binding-strap 17 is interierly flanged at both upper and lower edges, the upper flange 19 being preferably straight, 65 while the lower flange 20 is inwardly and upwardly curved, as is clearly shown in Figs. 4 and 5. The flanging operation tends to yieldingly retain this binding strap in its annular form, and the ends thereof may 70 easily be sprung apart for the insertion within the ring of the slip cover 13 or for applying the strap to the mouth of the vessel.

It will be apparent that after both parts of my closure have been applied to the 75 mouth of the vessel, the flanges of the binding strap 17 may be simultaneously subjected to the operation of spinning rolls, and the edge of the slip cover 13 firmly and tightly clamped against the upper face or 80 edge of the mouth of the vessel, the packing ring 16 serving to provide an hermetic seal.

When considered in connection with the container to which it is applied, an important feature of my invention is the curvature 85 which I have given to the lower flange 20 of the binding strap. It will be noticed that with this construction only the edge of this flange comes in contact with shoulder 12 with which the container is provided. It is 90 well known that where this flange is straight, and lies closely against said shoulder, it not infrequently happens that with a glass or brittle vessel during the spinning operation referred to the pressure exerted by the spinning rolls, with nothing between said rolls and said shoulder except a single layer of 95 thin metal, will break or crack the material at the mouth of the container and render the same unfit for use. However, by curving 100 the lower flange 20 in the manner shown, I first augment both the rigidity and the resiliency of said flange, due to its semi-cylindrical configuration, and, second, interpose 105 between the spinning roll and the shoulder not only a yielding body which takes up and dissipates destructive strains, but a resilient body which, under the forces which tend to restore its normal configuration, re-act through the upper flange 19 to more firmly 110 clamp the slip cover 13 in place.

It is well known that in order to render

available the elastic forces of metal to be formed, the exact shape desired must be exaggerated—that is to say, the metal must be bent or curved beyond the desired point—in order that it may have a tendency to return to the shape desired and through such tendency generate forces. It will therefore be apparent that with a flat lower flange, already snugly embracing the shoulder of the container, no such forces as those described could be created and any attempt to create them would almost invariably result in the fracture of the glass or other brittle substance of which the container is made. 10 It will be seen, however, that with the extreme edge only of my curved flange in contact with said shoulder, the change in configuration of said flange by the spinning roll may be carried beyond the desired point, 15 whereupon the elasticity of the metal will provide the clamping forces hereinbefore referred to. The same is undoubtedly true with the application of my invention to a sheet metal container, as shown in Fig. 5, 20 although in this case there is no danger of fracturing the container. The configuration of my lower flange, however, through the reacting forces generated by the spinning operation, gives me a better and a more permanent seal and tends to hold the closure 25 more rigidly and firmly in place.

Not second in importance to the feature of my invention already described, is the manner I provide for assembling the two parts 30 of my closure and holding the same together as one member for purposes of handling, packing, delivery and application. Heretofore, with closures of this character, it has been the practice, so far as I know, to leave 35 one edge of the binding-strap unflanged, this edge being flanged after the closure has been applied to the container, both flanging and sealing being effected through the spinning operation. These closures are frequently demanded as separate articles of manufacture. 40 Packers who secure their container from one source—as, for instance, when glass bottles or jars are employed—sometimes have to procure their containers from one source and 45 their closures from another, and it has been found to be exceedingly inconvenient to have the slip-covers delivered in one lot and the binding-straps in another, necessitating the assembling of these parts by the workmen 50 who are applying the same to the containers and completing the closure.

By flanging both edges of the binding strap in the first instance, the slip cover 13 may be readily placed within the flanged 60 ring by springing the butting ends thereof slightly apart, whereupon the resiliency of the metal will again close said ring and for the purposes mentioned will retain the slip-cover therein. With these two parts assembled in this manner, all that the work- 65

men who complete the closure have to do is to spring the binding-strap over the mouth of the bottle and thereby simultaneously slip the cover in place, whereupon the covered vessel is subjected to the action of the spinning rolls and the seal completed. 70

It will be seen that the binding-strap 17 is held in place by the rigidity given to the metal of which the strap is formed, through the effect of the spinning operation upon the 75 flanges. This rigidity has been found to be sufficient to insure an hermetic seal under all ordinary conditions. The forces due to this rigidity however, are not sufficient to withstand a positive lateral pull upon one of the 80 open ends of the ring which, when started, is easily stripped from the mouth of the container, permitting of the ready removal of the slip cover. For the purposes of facilitating this operation to removal, I provide the tongue 18, as described, which may be readily bent away from the side of the strap to provide a handle which may be grasped in the fingers and subjected to a force which will easily overcome the rigidity 85 with which the strap is retained in its annular shape and its grip upon the covered container.

I claim as new and desire to secure by Letters Patent.

95

1. A closure for containers comprising a slip-cover adapted to fit over the mouth of the container, and a binding strap of resilient metal peripherally surrounding said slip cover, both edges of said binding-strap 100 being flanged to provide jaws, the upper engaging the top edge of said cover and the lower to engage a shoulder on the container and said flanges serving to clamp said cover in place, and said lower flange being upwardly directed to present the extreme edge thereof only to said shoulder.

105

2. The combination, with a container having an exterior downwardly-directed shoulder near its mouth, of a slip-cover adapted 110 to fit over the mouth of the container, a packing-ring interposed between said cover and said mouth, and a binding-strap of resilient metal peripherally surrounding said slip-cover, both edges of said binding-strap 115 being flanged to provide jaws, the upper engaging the top edge of said cover and the lower engaging said shoulder on the container and clamping said packing-ring between said cover and said mouth, and said lower flange being upwardly curved to present the extreme edge thereof only to said shoulder.

120

3. A closure for containers comprising a slip-cover adapted to fit over the mouth of the container, the top of said cover being centrally depressed to provide a seat for a gasket, a gasket in said seat, and a binding-strap of resilient metal peripherally surrounding said slip-cover, both edges of said 125

130

binding-strap being flanged to provide jaws,
the upper engaging the top edge of said
cover and the lower to engage a shoulder on
the container and clamping said gasket be-
tween said cover and said mouth, and said
lower flange being circular-cylindrically
curved to present the extreme edge thereof
only to said shoulder.

In testimony of the foregoing I have here-
unto set my hand this 29th day of January, 1908.

HORATIO N. NORTON.
